UNITED STATES PATENT OFFICE.

EDGAR A. EDWARDS, OF CINCINNATI, OHIO.

MERCURY AIR-EXHAUSTER.

SPECIFICATION forming part of Letters Patent No. 257,679, dated May 9, 1882.

Application filed April 19, 1881. (No model.)

To all whom it may concern:

Be it known that I, EDGAR A. EDWARDS, a citizen of the United States, and a resident of Cincinnati, in the county of Hamilton and State of Ohio, have invented certain new and useful Improvements in Mercury Air-Exhausters, of which the following is a specification.

My invention relates to an improvement in mercurial air-pumps.

10 The first part of my invention consists in providing a receiver carrying a sufficiency of mercury, which reservoir is connected to guide-rods, and is elevated and depressed by cranks and pulleys, and is connected to a primary mercury exhausting receiver, so that the exhaustion of air can be carried on rapidly by elevating and depressing the reservoir carrying the mercury column. Suitable cocks for admitting and cutting off the air are provided.

20 The second part of my invention consists in providing a series of mercurial fall-tubes, combined with a horizontal common feed-tube, which connects at one or both ends with an elevated mercury-reservoir by means of a U-shaped supply-tube. This common feed-tube is connected to the receiver from which the air is to be exhausted, so as to utilize a compound series of falling tubes to hasten the exhaustion of air.

30 The third part consists in combining the first with the second part of my invention.

There are several other important features of my invention relating to detail parts of my exhauster, which will be fully explained in the following specification.

In the accompanying drawings, Figure 1 is an elevation of the machine embodying my invention. Fig. 2 is an enlarged view in sectional elevation, showing the construction of parts of my machine. Fig. 3 is an elevation of one of the supply-reservoirs, showing the guides upon which it travels broken off.

A A' represent the frame on which my exhauster is mounted.

5 B represents a mercury-reservoir, which is made of glass and provided with ears or metallic guides b, which connect with suitable guides, B'', so that by means of pulley B' and cord b' and crank b'' the reservoir may be rapidly raised and depressed.

C represents a primary exhaust-receiver,

which has traps e e' connecting it with the receiver or vessel from which the air is to be removed.

C' represents a tube leading to reservoir B. 55

C'' represents a flexible tube connecting parts B and C'.

c represents an air-escape tube.

c' represents a mercury air-seal, the end of tube c being below the surface of a mercury column in the vessel c'. In forcing the air out through the column of mercury it escapes out of the top of vessel c', the pipe c not fitting closely to the same. The mercury in vessel c' prevents the air from entering the pipe c to 65 destroy the vacuum.

c'' represents a receiver to collect surplus mercury, which is run from the exhaust-chamber C into seal-vessel c', so as to insure the complete exhaustion of the chamber C and 70 tube c, both of which are necessary to the displacement of the air in chamber C and pipe c. This portion of my invention can be used as an ordinary air-pump, and is much more rapid in its operation than others now in use. 75

D represents a series of fall-tubes, which are connected at the bottom to a common discharge-chamber, D', the discharge end of which is elevated to form a mercury air-seal to prevent the air forced out of the tubes D 80 from entering the ends of the tubes P, the lower ends of which are below the surface of a body of mercury in the chamber D'. The upper end of tubes D are connected to a common air-chamber, E, which has a pipe, E', and 85 this pipe is connected to a U-shaped tube, F, which in turn taps a reservoir, F'. This reservoir is shown as having a float, F'', in a body of mercury. When the chamber is empty the stem f, attached to float F'', strikes an electric 90 alarm contact, f', which is connected by wire to an alarm-box, H, and an alarm is sounded and more mercury is supplied from a reservoir, G. This reservoir is made to rise and fall between guide-rods G', and is connected to a 95 pulley, I, by cords and pulleys g and g'. Pulley I may be turned by crank or other suitable means.

J represents a waste-vessel, into which mercury is emptied from the discharge-chamber D'. 100

J' represents a flexible tube, and this may be made long enough to connect directly to

reservoir G, which can be lowered to receive the discharge from chamber D'. The common air-supply chamber E has a pipe-connection, e e', to the primary exhaust-chamber C.

5 K K' are chambers filled with material for absorbing the impurities and moisture arising from the mercury.

L represents the globe or vessel from which air is to be exhausted. It is connected by 10 pipes to chambers K K', and thence by pipe l to chamber E, which is also connected to the primary exhaust-chamber C.

S represents a bulb-chamber in pipe F. p represents a pipe with a strainer over the end 5 to remove the mechanical impurities from the mercury.

W represents a chamber forming an air-trap. The mercury is supplied into the chamber W by passing up through the pipe p, from 10 the upper end of which it passes into the said chamber.

U represents a cock with a stem, r, reaching 15 toward the bottom of chamber W when set in the position shown in Fig. 2. The mercury supplied from reservoir F' is forced through pipe F into strainer-chamber S, thence by pipe p into chamber W, when the air in the mercury rises above the mercury and the mercury is forced into the feed-tube E'. In order to keep 20 a constant supply in the series of pipes D, the sum of the areas of the orifices of these tubes is made smaller than the area of the supply-pipe E'. To allow the escape of air from chamber or air-trap W, a cock may be provided or 25 the cock U may be raised.

N represents a cock for connecting the chamber C alternately with pipes e and e', to exhaust the air from pipe e and escape the same through pipe e.

40 T represents a radiometer, which is employed simply to indicate approximately the vacuum of the exhaust apparatus.

R' represents a cock placed between the globe L and the exhausting apparatus, so that 45 the vacuum in the exhauster can be retained while globe L is removed and a new one placed in position.

O P' P'' R R'' represent a McCleod gage, with a stop-cock, Q, inserted below the globe 50 P', which may be used as a substitute for the ordinary mercury vacuum-gage to determine the vacuum-pressure.

The lower end of radiometer T is provided with a two-way cock, N', for connecting and 55 cutting off pipes e e'.

The primary portion of my apparatus (represented by the parts connecting to pipe e) may be separately employed as an ordinary pump. They are used for that purpose to remove rapidly the greater amount of air from the vessel L.

In order to make a very high vacuum, cock N is turned and the primary part is cut off, and the secondary or drop tubes are brought 65 into operation. This is accomplished by the mercury dropping from tube E', said tube

having small orifices immediately above drop-tubes D, through the tubes D into the escape D', whence it passes out pipe J' to be placed into the supply-tank G to be used over again.

It will be observed from the foregoing that the mercury-supply tube E' is suspended in an air-chamber over the drop-tubes, and connected therewith, and that the air-space between the mercury-supply tube and air-chamber is connected by an air-passage directly with an air-vessel, L, and consequently the mercury dropping from the tube E' will force out with it the air, thus making a higher vacuum in the air-spaces from the vessel L 10 around the tube E' and through the drop-tubes. In other words, as fast as the drops of mercury carry out particles of air from the air-chamber around the mercury-tube E' the air in the vessel L will descend to take its 15 place, as the vacuum-pressure must equalize itself in the continuous air-space from the vessel L down to the mercury seal at the bottom of the drop-tubes D. As the orifices in tube E' are very small, the mercury passes out in 20 small drops, and between each drop is carried a column of air. This process may be continued until a very high vacuum is produced. It is obvious that these drop-tubes are used to supplement the work of my primary pump.

The several stationary tubes and the cocks and chambers are all made of glass, as it is necessary to use the mercury pure as possible.

The cocks N N' Q R' U are all arranged vertically, their upper ends being surrounded by mercury or other similar matter in cups d, formed on the respective tubes in which they operate, to provide a seal-joint and prevent the escape or entrance of air to affect the working of the apparatus.

It is obvious that this exhauster may be used to remove elastic fluid gases of all kinds.

I claim—

1. An air-exhauster composed substantially of the primary exhaust-chamber C, having stop-cock N, pipe C' e and seal e', and reservoir B, combined with guide-rods, cord, and pulley, so as to be rapidly operated, in the manner substantially as herein set forth.

2. The exhaust-chamber C, with the tubes e e', connected to the top of said chamber, in combination with the seal cut-off cock N, substantially as herein set forth.

3. The combination of the series of drop-tubes D with the air-chamber E, feed-tube E', and discharge-chamber D', in combination with an elevated mercury-reservoir, F', for exhausting air from a vessel, L, in the manner substantially as herein set forth.

4. In combination with one or more drop-tubes, D, and reservoir F', the U-shaped tube F, with an air-trap, W, arranged to connect the parts, in the manner substantially as herein set forth.

5. In combination with the U-shaped tube F, the air-trap W and seal cut-off cock U, substantially as herein set forth.

6. In combination with the reservoir F, the float F'', and alarm f' H, the reservoir G, arranged to be raised and lowered by cord and pulley, in combination with the reservoir F', tube f, and drop-tubes D, substantially as herein set forth.

7. The combination of the primary exhausting apparatus B C with the compound series of drop-tubes D and feed-tube E' in air-chamber E and elevated mercury-reservoir F', for

exhausting air from a vessel, L, in the manner substantially as herein set forth.

In testimony whereof I have hereunto set my hand in the presence of two subscribing witnesses.

EDGAR A. EDWARDS.
